FOREIGN PATENT DOCUMENTS

DE 4029628 10/1991

Primary Examiner—Cathron C Brooks*Assistant Examiner*—Kevin K Rudzinski(74) *Attorney, Agent, or Firm*—Perkins Coie LLP(57) **CLAIM**

The ornamental design for an aircraft luggage bin, as shown and described.

DESCRIPTION

FIG. 1 is a front perspective view of an aircraft luggage bin showing my new design in a typical environment.

FIG. 2 is an isolated front perspective view thereof.

FIG. 3 is a front cross-sectional view taken along line 3—3 in FIG. 4, the rear cross-sectional view being a mirror image.

FIG. 4 is a right side elevation view thereof; and,

FIG. 5 is a bottom plan view thereof.

The broken lines shown are included for the purpose of illustrating environmental structure and form no part of the claimed design.
